CLAIM

The ornamental design for a onesie, as shown and described.

DESCRIPTION

FIG. 1 is a front perspective view of a onesie showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of detail "9" identified in FIG. 1;

FIG. 10 is an enlarged view of detail "10" identified in FIG. 2; and,

FIG. 11 is an enlarged view of detail "11" identified in FIG. 2.

The broken lines in the drawings are for the purpose of illustrating portions of the onesie that form no part of the claimed design. The dash dot dash lines are for the purpose of illustrating the enlarged view indicators and form no part of the claimed design.

1 Claim, 11 Drawing Sheets
